Anthony W. Jones of New York N. Y. Assignor to
E. R. Brown of Albany N. Y.
Letters Patent. No 325. Dated Sept. 25. 1850.

The Schedule referred to in these Letters Patent and making part of the same.

To all whom it may concern:

Be it known that I Anthony W. Jones of the City of New York have produced a new Ornamental Design for a Parlor Stove and I do hereby declare that the annexed and accompanying drawings are full and accurate delineations of the Ornamented parts, with their several ornaments.

These several ornamental parts being intended to apply to the Stove called the "Cabinet top parlor Cooking Stove" for which Letters Patent were granted to Edward

Dec. 325

2

R. Brown on the fifth day of June 1849.

What I claim as my production and desire to secure by Letters Patent is the combination & arrangement of Ornamental figures or forms represented in the accompanying drawings, forming together an ornamental design for a Parlor Stove.
